UNITED STATES PATENT OFFICE.

THOMAS BRINDLE AND MERRILL O. STEERE, OF PAWTUCKET, RHODE ISLAND.

LOOM.

SPECIFICATION forming part of Letters Patent No. 634,681, dated October 10, 1899.

Application filed February 21, 1899. Serial No. 706,378. (No model.)

To all whom it may concern:

Be it known that we, THOMAS BRINDLE and MERRILL O. STEERE, of Pawtucket, in the county of Providence and State of Rhode Island, have invented certain new and useful 5 Improvements in Looms, of which the following is a specification.

This invention has relation to looms, and has for its object to increase the capacity and 10 efficiency thereof.

The invention consists in the novel features of construction and arrangement which we will now proceed to describe and claim.

Of the accompanying drawings, forming a 15 part of this specification, Figure 1 represents a front elevation of a loom constructed in accordance with our invention with parts broken away. Fig. 2 represents a vertical sectional view thereof. Fig. 3 represents a 20 plan view of part of the shafting, both the lays beating up together and then receding together. Fig. 4 represents a detail perspective view of part of the lay.

The same reference characters indicate the 25 same parts in all the figures.

Referring to the drawings, *a* designates the loom-frame. *b* designates the drive-pulley, mounted at one end thereof on the crank-shaft *d*, and *c* *c* designate two lays mounted 30 at opposite sides of the loom on lay-swords *c' c'*, which are pivoted at their lower ends in the ordinary manner. The crank-shaft *d* runs longitudinally of the loom, substantially in the center thereof, and has cranks *d' d'* 35 connected by pitmen *d² d²* to the respective lays *c c*. When the pulley *b* is driven by power imparted from the belt, the crank-shaft will be revolved and will operate to rock the lays. Those cranks *d' d'* which operate the 40 lay *c* on the right side of the loom are, as seen in the drawings, set at a half-turn or one hundred and eighty degrees from the cranks *d' d'*, which operate the lay *c* on the left side of the loom, so that the two lays when the crank-shaft *d* is revolved alternately approach and 45 recede from each other. This arrangement equalizes the strain and rack due to the operation of the lays, since the forces due to the

inertia of the lays and connecting parts act in opposite directions and tend to neutralize 50 or balance each other. Each side of the loom is provided with suitable harnesses *e e*, having heddles, through which the warp-threads pass to form the shed, the number of these harnesses being subjected to variation to suit requirements, as will be readily understood. 55

The harnesses *e* in the arrangement shown are mounted in suitable guides on the loom-frame and positively operated in a familiar manner by bell-cranks *e¹ e²*, connected by links *e³ e⁴* with the harnesses and by longitudinal rods *e⁵* with harness levers or jacks *f*, hooked at their upper ends and fulcrumed on a rod *f'*. The two sets of levers or jacks *f f* for operating the harnesses on the two sides of the 65 loom are operated by two sets of path-cams *g g* on a cam-shaft *g'*, the levers having rolls occupying the paths in said cams. The shaft *g'* is mounted in suitable bearings attached to the loom-frame *a* and is provided with a 70 bevel-gear *g²*, which meshes with a bevel-gear *h'*, mounted on the end of a shaft *h*, which runs longitudinally of the loom, and said shaft *h* is connected by suitable gearing *y y' y²* with the driving or belt pulley *b* on the crank-shaft *d*, so that when the latter is rotated the shaft *h* will be revolved and will operate the 75 cams *g*.

Our invention, further, contemplates an improvement particularly adapted to narrow-ware looms—such as those for weaving tape, webbing, fringe, ribbon, &c.—with a view to increasing the capacity and effectiveness of such looms, and to this end we provide constructions as follows: *k* and *m* represent shuttles arranged in two banks, the one above the other, on the lay *c*, the said shuttles being positively driven, as is usual in narrow-ware looms, and by means of a novel driving mechanism to be hereinafter described. *k' k'* 80 *m' m'* are shuttle guides or races attached by screws *k⁴ k⁵* and *m⁴ m⁵* to the top portion or back frame *c³* of the lay. Between the shuttle-guides of each series are located the reed-spaces occupied by the reeds *k² m²*. The shuttles are moved, as is customary, across the 85 90 95

reed-spaces from one pair of shuttle guides or rests to the next pair, so as to pass the weft or filling thread through the shed formed in the warps by the harnesses. It will be noted that the reeds k^2 belonging to the upper set or bank of shuttles are located directly above or opposite the shuttle rests or guides provided for the lower set of shuttles, and, vice versa, the reeds m^2 of the lower bank 10 are located opposite the shuttle-rests of the upper bank.

Each of the shuttles $k m$ is provided with an individual rack $k^6 m^6$, the racks of the upper bank being on the lower side of the shuttles and those of the lower bank being on the upper side of the shuttles, and located in slots in the inner or adjoining guides $k' m'$ of each shuttle-bank are small gear-pinions $k^3 m^3$. Two of these pinions are provided for each 15 shuttle, and the screws $k^5 m^5$, which attach the inner guides $k' m'$ to the lay-back e^3 , serve as shafts or pintles for said pinions. Located between the upper and lower sets of pinions $k^3 m^3$ and running longitudinally of the lay c 20 is a single rack-bar o , having racks $o' o^2$ on its upper and lower edges engaging the teeth of the two sets of pinions $k^3 m^3$. At intervals along the rack-bar o the latter is formed with slots o^3 , occupied by headed screws or guide- 25 studs o^4 , screwing into the lay, whereby the rack is guided in its longitudinal movements, the studs being preferably surrounded by rollers o^5 . The screws o^4 may also serve to attach to the lay a guard-strip o^6 , covering 30 the outside of the rack-bar and having offsets or lips o^7 covering the outside of the rack-bar between the shuttle-guides $k' m'$, said guard-strip effectually preventing access of dust to the rack-bar. It will be seen that the recip- 35 ration of the rack-bar o operates both sets of shuttles $k m$ simultaneously across the reed-spaces in front of the reeds $k^2 m^2$.

For the purpose of operating the rack-bars o on the two sides of the lay mechanisms are 40 provided consisting of shafts $i i'$, provided with bevel-gears $i' i'$, meshing with a bevel-gear h^2 on the shaft h . Each shaft i has at its outer end a crank i^2 , operating in a vertical slot formed in a slide j . The latter is 45 mounted in suitable guides on the loom-frame and is connected with opposite ends of the rack-bar o by means of rods j' and straps j^2 , the latter of which pass over suitable guide-pulleys $p p'$ on the lay c . The shaft h is rotated from the belt-pulley b by the connections before described, and its rotation imparts motion to the crank i^2 , and it in turn 50 reciprocates the slide j , thereby moving the rack-bar o to and fro in the lay c . The gear- 55 ing is suitably proportioned to move the rack-bar once for each backward oscillation of the lay.

$q q$ represent the warp-beams for supplying the warps to the banks of shuttles. $s s$ 60 represent tension-weights for the several sets

of warp-threads, and $t t$ represent guide rods or rolls for the warp-threads. $u u$ represent the two breast-beams carrying breast-rods $v' v'$, over which the finished fabrics pass. Any suitable or approved forms of take-up and let-off may be provided, and the same being familiar in the art need not be described.

The novelty of our invention with respect to the arrangement of the two banks of shuttles and the reeds in the lay consists in locating the reeds in one bank opposite the shuttle-rests of the other bank, and vice versa, so that fabrics woven by the respective banks of shuttles and reeds will alternate with each other. This permits the fabrics to be led to 75 their respective take-ups without changing their vertical direction, and it also puts each fabric in sight and permits ready access to each fabric. The arrangement, furthermore, prevents the chafing of the warp-threads in 80 the two sets of reeds, which would occur were the fabrics superposed or formed one directly above the other and the top threads of one shed allowed to cross the bottom threads of another shed. We are thus enabled to use 85 different kinds and colors of yarn for the upper and lower fabrics, a proceeding which would be attended with great disadvantages 90 were the warps superposed, as described.

Our improved construction of rack-gear- 95 ing for operating the shuttles is simple and easy-running, and it has the advantage of putting the rack in sight and giving easy access thereto. We prefer to run the racks on the two sides of the loom in opposite direc- 100 tions to effect a balance, this being accomplished by setting the wrist-pins i^2 on either side of the loom in opposition, as shown in Fig. 3. This balance, together with that provided by mounting the lays to operate in 105 opposition, enables us to run the loom at a higher speed than heretofore and produces very even fabrics.

It will be seen from the foregoing that by 110 means of our improvements the output of a loom may be greatly increased.

Such of the operating parts of the loom as are well known and not essential to the illustration of our invention have been omitted in the drawings.

We claim—

1. A loom having a suitable frame, two lays located on opposite sides of the loom, a single crank-shaft having cranks for operating said lays, and connections between said cranks and the lays, the said cranks and connections being constructed and arranged to operate in opposition.

2. A loom having a suitable frame, two lays located on opposite sides of the loom, a single crank-shaft having two sets of cranks for operating the respective lays, the cranks of one set being mounted on a half-turn with respect to the cranks of the other set, whereby the lays are caused to alternately approach 130

and recede from each other, and pitman connecting said cranks with the lays.

3. The combination with the lay-back and the shuttle-guides $k' m'$ and the intervening 5 reeds, of the rack-bar o , and the dust-guard strip o^6 having offsets or lips o^7 covering the rack-bar between said guides $k' m'$.

In testimony whereof we have affixed our signatures in presence of two witnesses.

THOMAS BRINDLE.
MERRILL O. STEERE.
